Fig-5

Fig-6

Fig-7

FIG. 1 is a perspective view illustrating a wheeled carrier for boats showing my new design;

FIG. 2 is a top plan view thereof;

FIG. 3 is a front elevational view thereof;

FIG. 4 is a rear elevational view thereof;

FIG. 5 is a bottom plan view thereof, with the wheels fragmentarily shown for convenience of illustration;

FIG. 6 is a left-end elevational view thereof; and

FIG. 7 is a right end elevational view thereof.

I claim:

The ornamental design for a wheeled carrier for boats, as shown.
